(57) **CLAIM**

The ornamental design for an adjustable soffit vent door system, as is shown and described.

DESCRIPTION

FIG. 1 is a perspective view of a front side of an adjustable soffit vent door system in a closed position.

FIG. 2 is a front side view of an adjustable soffit vent door system in a closed position.

FIG. 3 is a back side view of an adjustable soffit vent door system in a closed position.

FIG. 4 is a perspective view of a front side of an adjustable soffit vent door system in an open position.

FIG. 5 is a front side view of an adjustable soffit vent door system in an open position.

FIG. 6 is a back side view of an adjustable soffit vent door system in an open position.

FIG. 7 is a perspective view of a front side of an adjustable soffit vent door system in an open position; the view showing the adjustable soffit vent door system in a partially open position.

FIG. 8 is a perspective view of a front side of an adjustable soffit vent door system in an open position; the view showing the adjustable soffit vent door system in a partially open position.

FIG. 9 is a bottom view of an adjustable soffit vent door system in a closed position.

FIG. 10 is a perspective view of disassembled components of an adjustable soffit vent door system; and,

FIG. 11 is a bottom view of door panels of an adjustable soffit door vent system.

The broken lines showing portions of the adjustable soffit vent door system form no part of the claimed design.

1 Claim, 11 Drawing Sheets
